Willis W. Washburn

UNITED STATES PATENT OFFICE.

WILLIS W. WASHBURN, OF CHICAGO, ILLINOIS.

TELEPHONE INSTRUMENT.

SPECIFICATION forming part of Letters Patent No. 684,963, dated October 22, 1901.

Application filed November 5, 1900. Serial No. 35,487. (No model.)

To all whom it may concern:

Be it known that I, WILLIS W. WASHBURN, a citizen of the United States, residing at Chicago, in the county of Cook and State of Illinois, have invented a certain new and useful Improvement in Telephone Instruments, (Case No. 1,) of which the following is a full, clear, concise, and exact description, reference being had to the accompanying drawings, forming a part of this specification.

My invention relates to telephone instruments; and its principal object is to provide a device of this kind which can be used either as a transmitter or a receiver, which can be constructed at a very low cost, and will at the same time involve simplicity of operation and construction and efficiency of action.

In the accompanying drawings, Figure 1 is a longitudinal section of a telephone instrument embodying my invention. Fig. 2 is a view, partly in elevation and partly in longitudinal section, of the same in a position at right angles transversely to the position in Fig. 1. Fig. 3 is a transverse section taken 25 on line 3 3 in Fig. 2.

In the telephone instrument illustrated a metallic cylindric shell 1, preferably brass, is inclosed within an insulating cylindric shell 2, preferably composed of hard rubber or vulcanite. A metallic cup 3, also desirably composed of brass, is secured, as by soldering, to the lower end of the cylindric shell 1, this cup 3 having an annular shoulder 4, upon which the cylindric shell 2 rests. The upper 35 end of the metallic shell 1 is threaded, and a cap 5, of insulating material, such as vulcanite, is screwed upon the outer end of the shell 1. A diaphragm 6 is arranged across the lower end of the cup 3, and a mouth or 40 ear piece 7 is fitted to the lower end of the cup 3, as by having a flange 8 adapted to surround the lower end of the cup 3 and screw-threaded, so as to correspond with screw-threads on said cup 3. The diaphragm 6 is 45 fitted between the abutting surfaces of the cup 3 and the mouthpiece 7. A permanent magnet 9 is confined within the metallic shell 1, the said magnet being a horseshoe-magnet and having its opposite sides extended length- 50 wise of the shell 1 and the ends thereof situated near the lower end of said shell. One

of the ends of said magnet 9 is provided with a pole-piece 10, composed of soft iron and extended downwardly, so that its end lies close to the diaphragm 6. This pole-piece 10 has 55 its lower end made cylindric in form and is arranged so as to lie behind the central portion of the diaphragm 6. The other end of the magnet 9 is provided with a pole-piece 11, which is also composed of soft iron and is extended substantially to the diaphragm 6. The pole-piece 11 is tubular in shape and 60 incloses the pole-piece 10, so that a small annular space intervenes between the two. A coil 12 of wire is arranged about the pole-piece 10 and within the pole-piece 11. The ends of the coil 12 are led out of the pole-piece 11 through small apertures formed in a piece of insulating material 13, which is fitted 65 into a longitudinal slot formed in the pole-piece 11. The ends of the wires led out through the insulating-strip 13 are connected with binding-posts 14 14. The pole-piece 11 has its upper portion screw-threaded, and this portion fits and screws into a correspondingly- 70 screw-threaded portion of the metallic cup 3. A set-screw 15 is screwed into one side of the cup 3, so as to bind against the screw-threaded 75 portion of the pole-piece 11.

The telephone instrument as thus constructed possesses high efficiency and an exceedingly-sensitive action and at the same time has such mechanical features that it can be readily and easily put together and taken apart and when put together will be very 80 strong and durable.

What I claim as my invention is—

1. In a telephone instrument, the combination with an inclosing shell or casing having a cup-shaped metallic portion, of a horseshoe-magnet arranged within said shell or casing and having one of its ends provided with a solid pole-piece and the other provided with an annular pole-piece inclosing the solid pole-piece, the said annular pole-piece being 90 screw-threaded and the said cup-shaped portion of the inclosing casing being correspondingly threaded so that the pole-piece can be 95 screwed into the cup-shaped portion to hold the magnet in position in the instrument.

2. In a telephone instrument, the combination of a metallic cylindric shell, an in-

sulating-shell arranged outside of the metallic shell, a cup-shaped metallic portion secured to the said cylindric shell and having a screw-threaded socket below its connection with said cylindric shell, a cap composed of insulating material and fitted upon the outer end of the metallic shell, an insulating mouth or ear piece fitted to the cup-shaped portion, a diaphragm arranged within the said mouth or ear piece, a permanent magnet arranged within the metallic shell and having one of its ends provided with an annular pole-piece adapted to inclose the pole-piece of the other end, the said annular pole-piece having a screw-threaded portion adapted to fit within the screw-threaded socket of the said cup, a coil of wire arranged between the pole-pieces, an insulating-strip arranged in a slot in an annular pole-piece and having apertures through which the wires within said pole-piece can be extended, and binding-posts to which said wires are connected, substantially as described.

3. In a telephone instrument, the combination with a horseshoe-magnet having its ends provided with longitudinally-extending pole-pieces, one of which is tubular in form and is arranged to inclose the other, of an inclosing shell or casing for said magnet, the said shell or casing being arranged to engage the tubular pole-piece so as to hold the mag-

net in position in such shell or casing, substantially as set forth.

4. In a telephone instrument, the combination with an inclosing shell or casing having a screw-threaded socket, of a horseshoe-magnet having its ends provided with pole-pieces, one of which is tubular in form and is arranged to inclose the other pole-piece and is provided with a threaded portion adapted to fit into the screw-threaded portion of the shell or casing, substantially as set forth.

5. In a telephone instrument, the combination of a tubular metallic shell having one of its ends screw-threaded, a cup-shaped structure having its smaller end secured to said metallic shell, an insulating-shell inclosing the metallic shell, a cap having a screw-threaded portion adapted to fit the threaded portion of said metallic shell and holding the insulating-shell against the cup-shaped structure, a mouth or ear piece fitted to the cup-shaped structure, and a diaphragm interposed between the ear or mouth piece and the flaring end of the cup-shaped structure, substantially as described.

In witness whereof I hereunto subscribe my name this 1st day of November, A. D. 1900.

WILLIS W. WASHBURN.
